UNITED STATES PATENT OFFICE.

JOHN ROGERS FLANNERY, BENJAMIN E. D. STAFFORD, AND ETHAN I. DODDS, OF PITTSBURGH, PENNSYLVANIA, ASSIGNORS TO FLANNERY BOLT COMPANY, OF PITTSBURGH, PENNSYLVANIA.

STAY-BOLT STRUCTURE FOR BOILERS.

1,203,517.

Specification of Letters Patent. Patented Oct. 31, 1916.

Application filed February 29, 1916. Serial No. 81,262.

To all whom it may concern:

Be it known that we, JOHN ROGERS FLANNERY, BENJAMIN E. D. STAFFORD, and ETHAN I. DODDS, citizens of the United States, and residents of Pittsburgh, in the county of Allegheny and State of Pennsylvania, have invented certain new and useful Improvements in Stay-Bolt Structures for Boilers; and we do hereby declare the following to be a full, clear, and exact description of the invention, such as will enable others skilled in the art to which it appertains to make and use the same.

This invention relates to improvements in stay bolt structures for boilers,—the object of the invention being to provide simple and efficient means whereby a tell-tale opening in the stay bolt may be normally sealed against the entrance of dust, etc., and whereby, when the bolt becomes fractured, cracked or broken, the said tell-tale hole will be opened to the passage and discharge of water or steam to denote the damaged condition of the bolt.

With this and other objects in view, the invention consists in certain novel features of construction and combinations of parts as hereinafter set forth and pointed out in the claims.

The accompanying drawing, is a sectional view of a stay bolt structure showing an embodiment of our invention.

1 represents the outer sheet of a boiler having a threaded opening for the accommodation of an externally threaded sleeve 2. The sleeve 2 projects beyond the outer boiler sheet 1 and receives a cap 3 which is preferably curved to conform to the curvature of the head 4 of the stay bolt 5, said head having a rocking bearing within the sleeve 2. The cap 3 is made with a central opening 6 which is normally closed by a thin disk 7 of soft or frangible metal or other material which may be easily destroyed or broken by impact. The disk 7 is normally held in place by the engagement of a tubular plug 8 screwed into an annular boss 9 on the cap.

The stay bolt is made with an axial tell-tale hole or opening 10, a portion 11 of which within the head of the bolt preferably being somewhat enlarged and open at the outer end of the bolt head in line with the disk or closure 7 in the central opening of the cap.

The larger portion 11 of the bore of the tell-tale hole or opening serves to receive a plunger or projectile 12 having a pointed end portion 13, and within the smaller portion of the bore of the tell-tale hole, a material or compound 14 is placed which, when subjected to the action of moisture, will cause the setting up of reactions which will result in the generation of gas having sufficient pressure to expel the plunger or projectile 12. As an example of the material which might be employed in the tell-tale hole, metallic sodium may be mentioned.

The wall of the larger portion 11 of the tell-tale hole is made with an annular groove 15 which receives the beaded or enlarged edge 16 of a cone 17 made of soft or readily penetrable metal disposed to inclose the pointed end portion 13 of the plunger or projectile and normally prevent the entrance of moisture to the material behind the projectile. The space within the portion 11 of the tell-tale bore may contain stiff grease or other easily penetrable packing 18 which will serve to augment the cone 13 in normally excluding moisture.

Under normal conditions, the material and devices within the tell-tale opening will serve to exclude dust, etc., which might clog said tell-tale hole, but if the bolt should become fractured, as indicated at 19, water will enter the hole or bore 10 and come into contact with the material contained in said hole or bore. The result will be the setting up of reactions which will cause the generation of gaseous pressure sufficient to expel the projectile and cause its pointed end to open the conical envelop 17 and then penetrate the frangible disk 7 in the cap 3, thus opening the tell-tale hole to the atmosphere. Pressure of water and steam entering the tell-tale hole of the fractured bolt will now clean out said hole sufficiently to permit the escape of such water or steam through the opening in the cap and thus denote the damaged condition of the bolt.

Slight changes might be made in the details of construction of our invention without departing from the spirit thereof or limiting its scope and hence we do not wish to restrict ourselves to the precise details herein set forth except as defined by the scope of the appended claims.

Having fully described our invention

what we claim as new and desire to secure by Letters-Patent, is:—

1. A stay bolt having a tell-tale hole, a pointed projectile within said tell-tale hole, a means within said tell-tale hole for expelling said projectile upon the entrance of moisture, and a destructible envelop encircling the end of the pointed projectile.

2. A stay bolt having a tell-tale hole, a pointed projectile therein, means in said tell-tale hole for expelling the projectile upon the entrance of moisture, and a destructible envelop inclosing the pointed end of the projectile and engaging the wall of the tell-tale hole to normally exclude moisture.

3. A stay bolt structure comprising a stay bolt having a tell-tale hole, a cap over the

head of the bolt and having a central opening, a destructible disk normally closing said opening, a projectile within said tell-tale hole and having a pointed end portion, means in said tell-tale hole for expelling said projectile upon the entrance of moisture, and a destructible cone inclosing the pointed end portion of the projectile and engaging the wall of the tell-tale hole.

In testimony whereof, we have signed this specification in the presence of two subscribing witnesses.

JOHN ROGERS FLANNERY.
BENJAMIN E. D. STAFFORD.
ETHAN I. DODDS.
